CLAIM

The ornamental design for an electrosurgical hand-piece, as shown and described.

DESCRIPTION

FIG. 1 is a perspective view of an electrosurgical hand-piece showing my new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a front end elevational view thereof;

FIG. 7 is a rear end elevational view thereof;

FIG. 8 is a perspective view thereof showing the tip portion in an extended position;

FIG. 9 is a top plan view thereof;

FIG. 10 is a right side elevational view thereof;

FIG. 11 is a bottom plan view thereof;

FIG. 12 is a left side elevational view thereof;

FIG. 13 is a front end elevational view thereof; and,

FIG. 14 is a rear end elevational view thereof.
